ANTENNA ROTATOR CONTROL HOUSING

Joseph M. Parriott, Westport, Conn., and Douglas A. Long, New York, N.Y., assignors to Cornell-Dubilier Electric Corporation, a corporation of Delaware

Filed May 25, 1964, Ser. No. 30,128

Term of patent 14 years

(Cl. D26—13)

FIG. 1

FIG. 2

FIG. 5

FIG. 3

FIG. 6

FIG. 4

FIG. 1 is a left side, top and front perspective view of an antenna rotator control housing, showing our new design;

FIG. 2 is a front elevational view;

FIG. 3 is a plan view;

FIG. 4 is a side elevational view;

FIG. 5 is a rear elevational view; and

FIG. 6 is a bottom view.

The dominant features of the invention reside in those portions of the drawing shown by means of full lines.

We claim:

The ornamental design for an antenna rotator control housing, as shown and described.
